(57) **CLAIM**

The ornamental design for an insulated food container, as shown and described.

DESCRIPTION

FIG. 1 is a top, front perspective view of an insulated food container embodying my design;

FIG. 2 is a side elevational view thereof, all sides being identical;

FIG. 3 is a top plan view thereof;

FIG. 4 is a bottom plan view thereof; and,

FIG. 5 is a perspective view of the insulated food container showing the outer lid exploded therefrom.
